(57) **CLAIM**

The ornamental design for a toy figurine leg, as shown and described.

DESCRIPTION

FIG. 1 is a front perspective view of a toy figurine leg showing the new design;

FIG. 2 is a front elevational view of the toy figurine leg of FIG. 1;

FIG. 3 is a rear elevational view of the toy figurine leg of FIG. 1;

FIG. 4 is a right side elevational view of the toy figurine leg of FIG. 1;

FIG. 5 is a left side elevational view of the toy figurine leg of FIG. 1;

FIG. 6 is a top plan view of the toy figurine leg of FIG. 1; and, FIG. 7 is a bottom plan view of the toy figurine leg of FIG. 1. The broken lines are for environmental and illustrative purposes only and are not part of the claimed design. In addition, the figures depict a right leg and foot of the toy figurine leg. The claimed design covers mirror images of the figures, i.e., a left leg and foot of the toy figurine leg.
